L. J. GAMOTY

TELEPHONE SILENCER

Filed Sept. 23, 1926

LUCIEN JOSEPH GAMOTY.
INVENTOR.

By *Otto Munk*
his Attorney

UNITED STATES PATENT OFFICE.

LUCIEN JOSEPH GAMOTY, OF BONDI, NEAR SYDNEY, NEW SOUTH WALES, AUSTRALIA,
ASSIGNOR TO SECROPHONES LIMITED, OF SYDNEY, NEW SOUTH WALES, AUSTRALIA, A COMPANY OF NEW SOUTH WALES.

TELEPHONE SILENCER.

Application filed September 28, 1926, Serial No. 137,948, and in Australia November 25, 1925.

This invention relates to apparatus of the sound deadener or suppresser type adapted to be attached to the mouthpieces of transmitters of telephones and whereby sound to be transmitted through such mouthpieces over a line or otherwise though not impaired in transmission is not capable of being heard by persons located in the vicinity of such mouthpieces, so that conversation can be carried on by users of telephones and sound waves thus produced can be transmitted privately.

The said apparatus consists of a hollow casing preferably constructed of metal though it may be constructed of other suitable material. Such casing may be of any appropriate pattern; it preferably is furnished with two hollow end wings through which air, or gases breathed by a person, are free to circulate.

In the front wall of the casing is an opening with which the lips of a person may be closely associated whilst conversation is being carried on into the mouthpiece of the telephone transmitter. The casing is adapted to be fitted onto the said mouthpieces.

Within the said wings may be arranged a series of plates which are disposed therein in spaced relation to each other. When the plates are fitted in the wings openings in the separate plates are in staggered relation with each other, so that sound waves impressed into the casing are caused to take a circuitous path, and in so doing such waves are not resounded outwardly of the casing, consequently persons in the vicinity of the telephone can not hear conversation which is being carried on.

Referring to the accompanying drawings in which embodiments of the invention are illustrated, Fig. 1 is a perspective view of the apparatus showing the mouthpiece opening at one side thereof; Fig. 2 a broken perspective view of the apparatus showing the side thereof which is connectable to a telephone mouthpiece; Fig. 3 is a section on plane 3—3, Fig. 1; Fig. 4 is a section on plane 4—4, Fig. 1; and Fig. 5 a broken sectional view showing modified construction of wing plates.

A hollow casing 1 of suitable design or pattern is provided; such casing may be of metal or other suitable material. At one side the casing 1 is furnished with an appro-

priate mouthpiece opening 2 adapted to 55 allow a person to speak closely to and into said mouthpiece without detriment to free breathing of such person. On the opposite side the casing 1 may carry a flange 3 surrounding an opening 18 in said side of the 60 casing 1, or it may be formed or fitted otherwise whereby the said casing may be suitably connected to the transmitter mouthpieces 4 of a telephone by means of the adjustable screws 5 or otherwise. The interior of the flange 3 65 may carry a packing washer 17 of rubber or other suitable material. The opening 18 is opposite to the opening 2 in the casing 1, so that a through opening is provided in the 70 casing 1, in relation to the telephone mouthpiece 4.

Fitted to the casing 1 in any desired manner are oppositely disposed hollow end wings 6 and 7. The interior of such wings may be grooved as at 8 to receive the plates 9 which 75 are spaced from each other. Each of said plates 9 has a series of openings 10 therein. In the drawings the wings 6 and 7 are shown open ended and are of conical shape. Any suitable means may be utilized for securing the plates 9 in the wings 6 and 7; these means may consist of a through screw-rod 11 and tightening nuts 12 with thumb-nut 13. The rods 11 pass through the whole of the plates 9 and their inner ends engage tapped openings respectively in the end walls 14 of the 80 casing 1. In such end walls are the openings 15. When the whole of the plates 9 are assembled in the wings 6 and 7 respectively the openings 10 in such plates 9 and in the 85 end walls respectively will be in staggered relation, so that any sound waves transmitted to the casing 1 through a person speaking 90 thereinto will be caused to take a circuitous path through the openings 15 and 10 before they will be emitted through the openings 10 in the outer plates 9 of the wings 6 and 7. Atmospheric air is, however, free 95 to enter the casing 1 through the openings 10 and 15 and gases breathed into the casing 1 by a person speaking thereinto are also free to pass to atmosphere through said 100 openings.

Instead of constructing the series of wing plates 9 to flat disc formation they may be formed with pockets 16 (Fig. 5) whereby sound waves upon passing through either the openings 15 or 10 will be caused to enter 105

said pockets and have to pass about the side walls of such pockets in seriatim before such waves will be able to complete the circuit of staggered openings 10 and 15.

5 As the apparatus is fitted with means causing a circuitous path of the impressed sound waves before they are emitted from the apparatus, and as the casing 1 allows a person using the telephone to conveniently 10 carry on conversation with the mouth closely associated with the opening 2 in the side of the casing, the sound to be transmitted is not resounded about the telephone mouthpiece 4, and persons located thereabout cannot 15 hear the conversation which is being carried on, so long as the person using the telephone speaks directly into the casing 1 with the mouth in close association with the speaker opening 2 of the said casing. 20 Though the emission of clear sound from the casing 1 and wings 6 and 7 is prevented free transmission of sound waves is allowed through the apparatus.

What I claim as my invention and desire 25 to secure by Letters Patent is:—

1. A telephone silencer comprising a hol-

low casing having a through opening in one direction leading to the telephone mouth-piece and perforated end walls disposed in the opposite direction, tapered cylindrical members arranged over each end wall, and a series of spaced discs of increasing diameter held within the tapered cylindrical members, each disc having perforations in staggered relation to the perforations of adjacent discs to provide a circuitous path for the sound waves seeking exit therethrough. 30

2. A telephone silencer as claimed in claim 1, in which the interior wall of each tapered cylindrical member is stepped to accommodate the peripheral portion of the discs, and means for holding the discs seated in said steps. 40

3. A telephone silencer, as claimed in claim 1, in which the discs comprise flat plates 45 having concentric perpendicular walls projecting from their surfaces toward the adjacent discs of decreasing diameter.

In testimony whereof I affix my signature.

LUCIEN JOSEPH GAMOTY.
